PORTABLE ELECTRIC SPACE HEATER OR THE LIKE

David L. Painter, Evanston, Ill., assignor to Titan Manufacturing Co., Inc., Buffalo, N. Y., a corporation of New York

Application November 20, 1957, Serial No. 48,559

Term of patent 3½ years

(Cl. D81—10)

Fig. 1 is a top plan view of a portable electric space heater embodying my new design.

Fig. 2 is a front view thereof.

Fig. 3 is a bottom plan view thereof.

Fig. 4 is a rear view thereof.

Fig. 5 is a view of the right side thereof; the opposite side is substantially the same.

Fig. 6 is an enlarged detail view of a portion of the grill which covers the center area of the front and rear of the heater as indicated in Figs. 2 and 4, respectively.

I claim:

The ornamental design for a portable electric space heater, or the like, substantially as shown and described.
